UNITED STATES PATENT OFFICE.

CHARLES T. DRAPER, OF CLEVELAND, OHIO, ASSIGNOR TO THE DRAPER MANUFACTURING COMPANY, OF CLEVELAND, OHIO, A CORPORATION OF OHIO.

REVERSIBLE GATE FOR STEEL BARRELS.

1,103,176.

Specification of Letters Patent. Patented July 14, 1914.

Application filed February 6, 1914. Serial No. 817,029.

To all whom it may concern:

Be it known that I, CHARLES T. DRAPER, a citizen of the United States, residing at Cleveland, in the county of Cuyahoga and State of Ohio, have invented certain new and useful Improvements in Reversible Gates for Steel Barrels, of which the following is a specification.

My invention relates to an improved reversible gate for steel barrels, and the like, and has for its object the provision of a controlling member for relatively thick or viscous fluid commodities, which member may be reversed in position and shipped, interiorly of the barrel. It is obvious that a gate of this type requires an ample clearance to facilitate the flow of the fluid, hence the actual closure part preferably is provided before the mouth of the faucet, and thereby its bore is left unobstructed. A gate of this type, however, is very likely to be accidentally opened in shipment, and accordingly I have provided one of such construction that it is automatically and permanently locked when reversed in position within the bung-hole of the barrel.

Briefly described, my improved gate comprises a faucet rearwardly flanged for the purpose of clamping the same at the bung-hole opening. Externally pivoted upon said faucet there is provided a closure member having U-shaped arms which terminate in angularly extending lugs adapted barely to clear the sides of the bung-hole when the gate is reversed or inserted interiorly of the barrel. Said lugs, however, are positioned so that they are entirely free of the bung-hole opening, when the gate is in its extended or operative position, and in consequence, it is unlocked for use when protruding from the barrel, but locked in closed position when reversed therein.

Details of my improvement will be more readily explained by making reference to the accompanying sheet of drawings, wherein:

Figure 1 is a fragmentary sectional view through the bung of a steel barrel, showing my improved gate in its reversed and closed position by full lines, and its extended and open position by dotted lines. Fig. 2 is a vertical sectional view thereof on line 2—2, Fig. 1.

Throughout both figures, the same reference characters have been applied to indicate similar parts.

The head *a* of barrel *b* is provided with a sleeve-like bushing *c* at the bung-hole, of sufficiently large diameter as will barely permit the insertion and withdrawal of the improved gate of my invention. This gate comprises a faucet *d*, having a rear flange *e*, and the bore of said faucet preferably is unobstructed and its inclination is slight, in order to afford the freest possible flow for such fluids as molasses, varnishes, etc. A U-shaped frame *f* having a forward thumb-piece *f'*, mounts the closure part *g* before the mouth of faucet *d* in position either to clear the bore or entirely close it; these parts being of the same arc or curvature. Frame *f* preferably is exteriorly pivoted at *h* upon the faucet and is provided with angularly extending lugs *f''*, which are adapted to lie approximately within the lines of the faucet adjacent to its flange when the gate is closed.

As generally indicated in full lines of the longitudinal sectional view (Fig. 1) but better illustrated by the cross-section of Fig. 2, these lugs *f'* terminate closely adjacent to the wall *b'* of the bushing, so that the closure *g* may not be opened while the gate is in its reversed position. An inner pin *f''* positioned within frame *f*, is adapted to play between the stops or limit-members *d'* provided adjacent to the mouth of the faucet and restrict the movement of the closure part. Flange *e* superposed upon a gasket *e'* and covered by the plate *e''* is clamped in its reversed position by means of the perforated screw-cap *i*, so that the barrel affords no protruding parts during shipment, yet the bung-hole is completely closed and the gate is locked against accidental opening. Merely by removing the cap *i* and reversing the gate to its dotted line or extended position, Fig. 1, wherein it is held by the screw-cap, it is apparent that the contents of the barrel may be drawn off through the gate, in the usual manner. In this position, the lugs *f''* clear the adjacent parts of the securing cap, so that the closure part is free to be actuated into its open position shown in dotted lines, and permit the flow of the contained fluid.

Having now described the structure of my

improved gate, I claim as new and desire to secure by Letters Patent, the following:—

1. The combination with a fluid-receptacle, of a sleeve-like member forming the bung-hole thereof, a flanged faucet insertible through said bung-hole, an exterior closure-part before the mouth thereof, an exterior member pivotally mounting said closure-part forwardly of the faucet, and a lug thereon, extending within said bung-hole and positioned closely adjacent to its wall when the faucet is interiorly disposed within the receptacle, substantially as set forth. 10
2. The combination with a sheet metal receptacle, of a sleeve-like bushing at the bung-hole thereof, a reversible gate adapted to pass through said bushing, comprising a rearwardly flanged faucet, a closure part mounted before the mouth thereof, a frame pivotally mounting said part rearwardly of the faucet; said frame terminating in lugs lying closely adjacent to the wall of the bushing when the faucet is reversed within the said receptacle, and means for removably securing the flange at the mouth of the bush- 20
- 25

ing either in reversed or extended position of the faucet, substantially as set forth.

3. The combination with a fluid receptacle, of an extended bushing forming the bung-hole opening thereof, a faucet provided with a rearward flange and an unobstructed bore adapted to be passed through said bushing and extend interiorly of the receptacle, a frame exteriorly pivoted upon the faucet, a gate carried by said frame before the mouth of the faucet, angularly extended parts upon said frame adapted to lie closely adjacent to the inner wall of the bushing when the faucet is in reversed position, and means for securing the flange over the bushing either in the reversed or extended position of said faucet, substantially as set forth. 30

In testimony whereof I do now affix my signature in the presence of two witnesses. 40

CHARLES T. DRAPER.
